UNITED STATES PATENT OFFICE.

BAGSTER ROADS SEABROOK, OF WINNIPEG, MANITOBA, CANADA, ASSIGNOR, BY MESNE ASSIGNMENTS, TO LYRADION MANUFACTURING COMPANY, OF MISHAWAKA, INDIANA, A CORPORATION OF DELAWARE.

TALKING MACHINE.

Application filed May 31, 1918. Serial No. 237,582.

To all whom it may concern:

Be it known that I, BAGSTER ROADS SEABROOK, of the city of Winnipeg, in the Province of Manitoba, Canada, have invented 5 certain new and useful Improvements in Talking Machines, of which the following is the specification.

The invention relates to improvements in talking machines and the general object of 10 the invention is to provide an attachment to a talking machine whereby the quality, modulation of the sounds reproduced from the record can be controlled to give a more natural reproduction of the recorded sound 15 and further to construct the attachment so that it can be set to accommodate the particular record being reproduced.

A still further object of the invention is to construct a talking machine having the 20 sound box tube entirely independent of the horn and to provide for the introduction of air to the horn at the point where the sound box tube delivers to the horn.

A still further object of the invention is 25 to construct the attachment in a simple, durable and inexpensive manner and so that it can be readily regulated by manipulation from the exterior of the machine.

With these and other ends in view I illustrate in the accompanying drawings such 30 instances of adaptation as will disclose the broad underlying principles which are involved without limiting myself to the specific details shown on the drawing and which 35 are described herein.

Fig. 1 represents a side view of the upper part of the talking machine showing my invention applied.

Fig. 2 represents an enlarged detailed 40 vertical sectional view through one of the upper corners of the machine body and showing my invention as applied and in side elevation.

Fig. 3 represents a front view of the parts 45 appearing in Fig. 2.

Fig. 4 represents a vertical sectional view centrally through the adjoining ends of the tone arm and the horn with my attachment applied.

Fig. 5 represents a horizontal sectional 50 view through the appliance, the section being taken in a plane directly above the sliding gate or shutter and looking downwardly.

Fig. 6 represents a vertical sectional view through the guide for the shutter. 55

Fig. 7 represents a perspective view of the pivoted lever for changing the position of the tone ring.

Fig. 8 represents an enlarged detailed side view of the adjusting screw associated with 60 the tone ring lever.

In the drawing like characters of reference indicate corresponding parts in the several figures.

1 represents the case or body of a talking machine having a closed top or motor board 2 which carries the tone arm 3 fitted with the sound box 4 provided with the usual stylus or needle 5. 6 represents a turn table on which the ordinary record 7 to be 70 reproduced is placed. 8 represents the horn of a machine and all of the above parts with the exception of certain changes which I make in the suspension of the horn are for the purpose of this description of any desired construction and for this reason a further description of them is not herein given. It is however to be understood that the turn table is operated by a motor usually mounted beneath the motor board 2 (not 75 shown) wound by crank B in the ordinary way and that the record is placed on the turn table and the stylus or needle is placed on the record in the usual manner.

The rear end of the tone arm 3, at its 85 base is provided with a horizontally disposed flange 9 that is pivotally attached in any desired manner, at 10; to the top 2 of the casing. As ordinarily constructed, at the end of the tone arm an opening 11 is 90 formed in the top 2 and the horn is attached on the underside of the top with the opening at the receiving end in direct connection with the opening 11 so as to form a continuous unbroken passage from the 95 former to the latter.

In my construction in this instance I make a radical departure from this procedure by not mechanically connecting the horn with the tone arm at all but I leave a clear unconnected space across which the sound is obliged to travel, by fastening the horn to a bracket 12 attached to the rear side of the case. Within this bracket or in any other relation I may place an amplifying control 100 125 slide 19 which may be used to cooperate

with a tone control ring 29 in any desired manner so as to modify the rendering of a subject according to the individual taste of the operator or the artistic demands of the 5 record which is being played.

I am aware that tone modifiers of various forms have been used heretofore, but I do not believe the cooperating structures such as I have disclosed have been so used. Of 10 the various features illustrated in the accompanying drawing that relating to the tone control is the more important. This is unique in that it does not depend on the usual expedient of varying the length of a 15 column of air to change the pitch or vibrations per second, but dependence is placed on a variation of the area of the space 39 where extraneous air is admitted to the sound waves which are directed from the 20 tone arm to the horn for amplification.

The amplifying control slide 19 has end-wise movement adjacent the guides 18 formed on strips 13 and 14 which are attached to the bracket 12. This slide 19 lies 25 on top of a plate 15 in which a round opening 16 is formed. The inner end of plate 19 has a semicircular recess 21 of about the same radius as that to which the opening 16 is formed and a small opening 20 is made 30 near the outer end of the plate into which the upper end of arm 25 extends. This arm is secured to a rod 24 and a knurled thumb piece 22 on the end of rod 24 is used to move the plate 19 to and fro so as to change the 35 size of the opening A.

The detail features of the tone control comprise a tube 26 secured in the opening 11 by nailing at 27 or otherwise. It is of the same internal diameter as the large end of 40 the tone arm 3. Its lower end is beveled from the inside outward as shown at 28 and it serves as a support on which the tone ring 29 slides up and down under the control of any desired mechanism.

In the present instance the tone ring 29 is 45 adjusted from outside the case 1 by means of screw head 37. This has a threaded stem 36 which engages the threaded portion of a suitable bushing set into an opening in the 50 side of the case. Its inner end is formed with two annular shoulders 34 and 35. At this point a slot 32 of the short arm of bell crank 30 passes over the grooved portion of stem 36. The bell crank 30 has its long arm 55 bifurcated as shown in Fig. 7 so as to pass half-way around the tone ring 29 and the extreme ends of this long arm are slotted for the reception of pins 33 which project from the side of the ring. The bell crank is suitably pivoted at 31. The operation will be 60 readily understood, as a twining movement of the head 37 will raise and lower the pins 33 and the ring 29 and will retain the adjustment as long as desired.

65 38 represents a comparatively short up-

wardly flaring tube permanently secured to the upper side of the bracket member 12, having the lower end thereof communicating directly through the opening A with the inner end of the horn and the upper end surrounding but spaced from the lower end of the tone ring. 70

From the above arrangement it will be apparent than an annular air passage 39 which simulates an inverted truncated cone, is 75 formed between the tone ring and the conical tube, which air passage can be varied in area depending upon the adjustment given the tone ring.

When the tone ring is in its uppermost 80 position this annular passage is greatest and it gradually decreases in area as the outer cylinder is moved downward owing to the flare of the tube. In actual practice I may adjust both the shutter and the cylinder 29 85 coordinately to the record which is to be played and when such an inner related adjustment is made I find that the record is produced in a superior manner.

By manipulating the shutter it will be 90 obvious that the sound opening at A to the horn can be enlarged or decreased with the result that the sound-waves admitted to the horn, when already partly amplified, are further modified at will. 95

With this attachment on a machine one can adjust it to get what he considers the correct reproduction of the record as the quality pitch and loudness of the sound can be varied to suit the ear of the hearer. 100

Whilst I have described the particular appliance for effecting the adjustment of the shutter and of the cylinder 29, still it will be understood that I do not limit myself to the related dimensions of the parts 29 and 105 38 as these can be readily modified without in the slightest departing from the spirit of my invention.

What I claim as my invention is:—

1. In talking machines, a horizontally pivoted tone arm, a tubular extension therefor passing beyond the tone arm pivot, an amplifying horn whose smaller receiving end is independently supported, long and short flaring ends to said horn, and an adjustable 110 tone ring slidable on the tone arm extension and projecting into the short flaring end of the horn but spaced apart therefrom whereby the area between the two parts may be changed at will to modify the delivery of 115 sound to the horn.

2. In sound reproduction, a tone arm, an amplifying horn, means for supporting the tone arm and amplifying horn spaced apart so that sound waves coming from the tone 125 arm will traverse the open area between said arm and horn before being delivered to the horn, and means for causing a current of air to be admitted variably as desired to the traversing sound waves. 130

3. The combination with the delivery end of the sound box tube of a talking machine, of a horn having the receiving end thereof flared and receiving but spaced from the delivery end of the tube, a cylinder slidably mounted on the delivery end of the tube and operating within the flaring end of the horn and means for adjusting the cylinder in respect to the horn to increase or diminish the area of the space between the horn and the tube.
4. In talking machines, a sound box connected to a tone arm, an amplifying horn in acoustic register with the delivery end of the tone arm but mechanically disconnected therefrom by a free air space so as to admit extraneous air at this point, and means for controlling such admission as desired within such air space.
5. In talking machines, an amplifying horn having large and small flaring openings joined by a neck of reduced diameter, means therein for changing the size of the free opening of the neck, a tone arm terminating within the small end of the horn but spaced apart therefrom, and means for reducing and enlarging said interspace to thereby cooperate with the horn to selectively modify the final rendition of the horn.
6. In talking machines, a horn having its receiving end flared, a tone arm terminating within said end but spaced apart therefrom, and a tone ring operative between the tone arm and the horn adapted to change the clear space between the ring and the horn through a reduction of its area.
7. In talking machines, an amplifying horn, a tone arm acoustically connected thereto but spaced apart therefrom, means comprising a sound box for causing sound waves to be delivered to the tone arm and from the tone arm to the horn, means for admitting an encircling air stream to surround and commingle with the passing sound waves proceeding from the tone arm, and means for controlling the admission of such air stream.
8. In talking machines, a horn, a tone arm disconnected from the horn to form a clear space between them, and means for variably connecting them in acoustic relation while spaced apart from each other by changing the dimension of said space.

Signed at Winnipeg, this 15th day of May, 1918.

BAGSTER ROADS SEABROOK.

In the presence of
G. L. ROXBURGH,
K. B. WAKEFIELD.
